BERNARD BRIODY, OF YOUNGSTOWN, OHIO, ASSIGNOR TO TRUSCON STEEL COMPANY,
OF YOUNGSTOWN, OHIO, A CORPORATION OF MICHIGAN

DOWEL FOR CONCRETE STRUCTURES

Application filed October 11, 1928. Serial No. 311,872.

In the construction of concrete roads, it has been found desirable in certain cases and under certain conditions to make them in sections, preferably in the form of reenforced slabs. It has furthermore been found that in order to prevent these slabs heaving or becoming elevated at their edges one above the other, it is desirable to dowel them together. As these sections or slabs have a certain amount of contraction and expansion, the anchoring therein of the dowels has created stresses, causing undesirable fractures.

The object of the present invention is to provide a dowel structure that will constitute an effective holding means and at the same time will permit free expansion and contraction, said means moreover being readily utilizable with the joint-forming strips and being positively positioned in place during the pouring of the concrete.

A preferred embodiment of the invention is illustrated in the accompanying drawings, wherein:

Figure 1 is a plan view of a road section indicating the dowel structures in place therein.

Figure 2 is a perspective view of a portion of the joint or parting strip and a dowel in place therein.

Figure 3 is a horizontal sectional view through the same.

Figure 4 is a view in elevation of the tubular section of the dowel.

Figure 5 is a cross sectional view on the line 5—5 of Figure 3.

The roadway, as shown, is designated A and is made up of concrete sections or slabs B, forming joints C. These joints are ordinarily formed by a joint or parting strip of sheet metal, a portion of which is shown at 6 in Figure 2. This parting strip as is well known is placed on the sub-base of the roadway in vertical position, and the concrete is poured against the opposite sides of the same. It is preferably provided with a central offset 7 that forms a key which effects an interlock between the adjacent ends or edges of the two slabs or sections B. In the present embodiment this offset portion 7 is provided

at intervals with openings 8 that receive the following dowel structures.

Each dowel structure consists of a rod section 9 in the form of a cylindrical rod that is passed through the opening 8 so that it is substantially centered therein. On one end portion of the rod section is fixed a transversely disposed supporting chair. This chair is preferably formed of a smaller rod bent to substantially U-form and inverted. Its central bar 10 is downwardly bowed to form a seat 11 that receives the rod. The two parts are electrically welded at their points of intersection. The end portions of the rod of the chair constitute legs 12 that preferably terminate in outturned feet 13. This chair, it will be understood, supports the rod section in substantially horizontal position.

On the opposite end portion of said rod section 9, and therefore on the opposite side of the strip 6 to the chair is slidably mounted a tubular dowel section 14. This is preferably made of relatively light sheet metal, and has its outer portion tapered off to a flat shape, said portion being bent downwardly to form a supporting leg 15. The tubular portion may have an inturned lug 16 stamped therefrom and constituting a stop against which the end of the rod section 9 is abutted.

In assembling the parts, it will be understood that the strip 6 is positioned on the sub-base and the rod sections 9 are passed through the openings 8 and supported by the chairs 10—13. The tubular sections 14 are then telescoped on the free projecting ends of the rod sections and are in like manner supported by their legs 15. The dowels are thus firmly supported and will not become displaced by the action of the concrete when poured upon and around them. When the concrete has set, the dowels of course remain embedded therein, but any contraction or expansion can take place freely without resistance because the free end of the dowel section 9 being enclosed in the tubular section 14, these parts can relatively slide on each other. Each, however, is not only embedded in its respective rod section or slab, but is anchored therein by the chair and leg 15. Their action in preventing the heaving of

one slab above the other is moreover entirely efficacious since no relative lateral movement can occur. This is for the reason that the rod section is actually embedded in the meeting end portions of adjacent slabs, though housed within the tubular section 14.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim, is:

1. A dowel structure for concrete roads and the like, comprising telescoping sections, each adapted to be embedded in adjacent concrete slab members, and supporting members secured to said sections and constituting permanent anchors therefor in the concrete.

2. A dowel structure for concrete roads and the like, comprising a rod section and a tubular section slidably telescoping the same, each of said sections having a supporting leg permanently connected thereto and permanently embedded in the concrete.

3. A dowel structure for concrete roads and the like, comprising a rod section, a supporting chair located transversely of and permanently secured to the outer end portion of said rod section and having depending supporting and anchoring legs, and a tubular section slidably telescoped on the free end portion of the rod section and having a depending supporting and anchoring leg at its outer end permanently connected thereto.

4. A dowel structure for concrete roads and the like, including a rod member and a transversely disposed supporting chair comprising a transversely disposed inverted substantially U-shaped bracket, permanently secured at its central portion to the rod member, with the depending end portions forming spaced supporting legs.

5. A dowel structure for concrete roads and the like, including a rod member and a transversely disposed supporting chair comprising a transversely disposed, inverted substantially U-shaped bracket having a downwardly bowed cross bar extending beneath and secured to the end of the rod member, with the depending end portions forming spaced supporting legs.

6. In combination a parting strip provided with an opening and a dowel comprising a rod section, a tubular section slidably telescoping the rod section, one of said sections passing through the opening in the parting strip, and means permanently secured to one of the members at one side of the parting strip for supporting the dowel during embedment in the concrete, said sup-

porting means being permanently embedded in the concrete.

7. In combination a parting strip provided with an opening, and a dowel comprising a rod section that passes through the opening, a supporting chair for the rod section fixed to one end of the same, a tubular section slidably telescoping the other end of the rod section and located on the opposite side of the parting strip to the chair, and a supporting leg for the outer end of the tubular section.

In testimony whereof, I affix my signature.

BERNARD BRIODY.
